G. H. BENJAMIN.
TUNNEL KILN.
APPLICATION FILED MAY 17, 1921.

1,415,011.

Patented May 9, 1922.

UNITED STATES PATENT OFFICE.

GEORGE HILLARD BENJAMIN, OF NEW YORK, N. Y.

TUNNEL KILN.

1,415,011.

Specification of Letters Patent. Patented May 9, 1922.

Application filed May 17, 1921. Serial No. 470,233.

To all whom it may concern:

Be it known that I, GEORGE HILLARD BENJAMIN, residing at New York, county of New York, State of New York, have invented a certain new and useful Improvement in Tunnel Kilns, of which the following is a specification.

My invention relates to improvement in tunnel kilns of the muffle type. The object of my invention is a construction by reason of which a more perfect temperature control is obtained than is possible in kilns as heretofore constructed. In tunnel kilns of the Dressler type, such for instance, as is disclosed in U. S. Patent No. 1,023,628, dated April 16, 1912, gas and air are burned in combustion chambers located on each side of the interior of the furnace and the heat generated by such combustion is radiated by the walls of the combustion chambers. In such construction shown, the gas and air is introduced into the forward end of each chamber, and the products of combustion withdrawn from the rear end of such chambers. In practice it is found that the highest temperature is at the point of entrance of the gas and air. This is not objectionable, but requires careful supervision of the gas and air supply, to prevent over-heating at the forward end of the kiln.

To avoid this objection, the construction disclosed in the patent of Benjamin, No. 1,268,204, dated June 4, 1918, was designed, and wherein the combustion chambers 5, on each side of the furnace, are divided into a series of combustion chambers, separately supplied with gas and air. This construction effects better distribution of heat, as the temperature zones along the interior of the kiln can be regulated as required. No one of these constructions, however, made any provision for the regulation of the heat radiated from the surfaces of the combustion chambers towards the goods carried through the kilns. In practice if the heat radiated from the combustion chambers at any point along the length of the kiln is too high, the effect will be to burn or check the surface of the goods transmitted through the kiln. It is, therefore, desirable to provide means for regulating the heat along any portion of the length of the kiln, so as to obtain uniformity of heating.

In my improved construction, the heating chambers on each side of the kiln are divided interiorly into two combustion cham-

bers, each of which is fed with gas and air, and each of which or both of which may be used to heat the air circulating around said chambers, and radiated from the opposed 60 surface of the oppositely located heating chambers towards the goods in the kiln, which arrangement permits a very perfect regulation, not only of the whole temperature of the kiln, but of the temperature exhibited along the sides of the kiln, towards 65 the goods moving through the kiln.

The accompanying drawings will serve to illustrate my invention, in which Fig. 1 is a vertical section taken along the line I—I 70 of Fig. 2.

Fig. 2 is a longitudinal section taken along the line II—II of Fig. 3, and

Fig. 3 is a horizontal section taken along the line III—III of Fig. 2. 75

Referring to the drawings, 5 indicates the body of the kiln which may be of any suitable construction. Located within the goods chamber 6 are heating chambers 7. Two of such chambers are shown arranged 80 longitudinally on each side of the goods chamber. The chambers 7 each consist of an outer enclosing wall 8, and two closed combustion chambers 9 and 10. The combustion chambers 9 and 10 are separated from 85 the enclosing wall 8 and from each other in such manner as to form a passage. The combustion chambers 9 and 10 are fed through separate gas and air burners 11 and 12, which project into the chambers at 90 one end. The products of combustion from such chambers pass out through flue 13 to chimney stack not shown. The heating chambers 7 are mounted above the bench 14 of the kiln in such manner as to provide an 95 air space around them and underneath them, the object of which arrangement is to permit circulation of the heated vapor in the interior of the chamber 6, around the heating chambers 7 and through the goods, as indicated by 100 the arrows in Fig. 1. It will be understood that no air is introduced into the goods chamber of the kiln after the goods carriages are in position, and that the heating of the goods is due to the air in the kiln, which is heated 105 from the combustion chambers. The air as it is heated passes upward in the direction indicated by the arrows, then downward and under the combustion chambers, the circulation being continuous. This circulation, 110 it may be pointed out, is the same as that described in the prior patents of Dressler,

Benjamin and others, and no point of novelty is claimed therefor.

The circulation of air within the heating chambers 7 is effected through the instrumentality of a blower 15, the air being introduced through a duct 16, and passes through the spaces between the outer surface of the chambers 9 and 10, and the enveloping wall 8, and then downward through the space between the chambers 9 and 10, and to the pump through the duct 17. The pump is provided with an air inlet duct 18 and an air relief valve 19, so that the passage of the air within the enveloping chambers 7 may be maintained constant, or modified as desired. 20 indicates a goods carriage and 21 goods on the carriage to be treated. 22 represents slide valves which may be used to control the air fed to the interior of the chambers 7, and which, it will be understood, may be used with the supply and relief valves of the pump 15.

The operation of my improved kiln is as follows:—

- 25 If the full temperature is to be generated, both the burners 11 and 12 are put into operation and combustion takes place in the chambers 9 and 10. If, however, it is desired that less heat be radiated from the inner sides of the heating chambers 7, which are opposed to the goods, the burners 11 are put into operation and combustion takes place in the chambers 9. If a higher heat is required, the burners 12 are put into operation; if a still higher heat, burners 11 and 12. Further, if a high temperature is required at the entrance of the kiln, the pressure of the gas and air introduced by the burners 11 and 12 may be low, in which case combustion takes place at the entrance end of the combustion chambers 9 and 10. If it is desired that the temperature be highest at the center of the kiln, the gas and air pressure are increased. Thus, by 45 manipulating the burners 11 and 12, and varying the gas and air pressure, the temperature at the entrance and middle of the kiln, and consequently at the exit entrance of the kiln can be regulated as desired.
- 50 It will be seen that when the burners in chamber 10 are not in operation, the surface of this chamber, opposed to the goods side of the chamber 7, is cooled by the incoming air; whereas the surface of chamber 9 is radiating heat, which heats the air passing through the exterior of the heating chamber, and which is directed through the goods on a carriage 20. It will be further observed that the temperature of the air circulated 60 by the blower 15 will depend upon whether

or not one or both of the burners 9 or 10 are in operation. In practice, the air circulated by means of the blower 15 may be entirely omitted, and circulation effected in any other well known manner.

Having thus described my invention, I claim:—

1. A tunnel oven comprising a main chamber through which goods to be heated can be caused to travel; a heating chamber on each side of the main chamber, but structurally independent of the walls thereof; each heating chamber consisting of an enclosing structure and two structurally independent combustion chambers located 75 therein.

2. A tunnel oven comprising a main chamber through which goods to be heated can be caused to travel; a heating chamber on each side of the main chamber, but structurally independent of the walls thereof; each heating chamber consisting of an enclosing structure and two combustion chambers located therein structurally independent and spaced as regards each other and the 80 walls of the enclosing chamber.

3. A tunnel oven comprising a main chamber through which goods to be heated can be caused to travel; a heating chamber on each side of the main chamber, but structurally independent of the side walls and roof of the main chamber; said heating chambers each divided into two separated combustion chambers located therein and an air circulating chamber, together with means 95 for introducing combustible gases into the said combustion chambers separately, and means for circulating air around said combustion chambers.

4. A tunnel oven comprising a main chamber through which goods to be heated can be caused to travel; a heating chamber on each side of the main chamber and structurally independent of the side walls thereof; each heating chamber consisting of an enclosing 100 structure and two structurally independent, spaced heating chambers located therein, together with means for introducing a combustible fluid into each of said combustion chambers separately, and means for introducing air into the heating chamber and 105 circulating it around the combustion chambers.

In testimony whereof, I affix my signature, in the presence of two witnesses,

GEORGE HILLARD BENJAMIN.
